UNITED STATES PATENT OFFICE.

WILLIAM E. GRAY, OF CHICAGO, ILLINOIS.

LEMON SQUEEZER.

Application filed November 18, 1920. Serial No. 423,770.

To all whom it may concern:

Be it known that I, WILLIAM E. GRAY, a citizen of the United States, and a resident of the city of Chicago, county of Cook, and 5 State of Illinois, have invented certain new and useful Improvements in Lemon Squeezers, of which the following is a specification.

My invention relates to improvements in 10 lemon squeezers and has for its object the provision of a lemon squeezer suitable for individual use at the table.

When a portion or slice of lemon or similar 15 citrus fruit is served with edibles at the table, it occasionally happens while squeezing the juice on the edibles that a spray of such juice finds its way on to the garments and even into the face of some one of the diners.

It is this undesirable occurrence that applicant 20 seeks to avoid, and as a remedy has perfected his lemon squeezer, a separate one being placed on the table for each diner.

Other objects will appear hereinafter.

An illustrative embodiment of the invention 25 is shown in the accompanying drawings, in which:

Fig. 1 is a side elevation of the device, parts being broken away;

Fig. 2 is a plan view thereof;

Fig. 3 is a side elevation of a modified 30 form, partly in section; and

Fig. 4, a plan view thereof.

The device comprises a housing or outer 35 frame, including the upper bracket member 6, connected to a lower case 7, which has an opening 8 in a depressed portion of the bottom thereof.

Any shape of case may be used and any 40 suitable shape of blade on the squeezers to fit the case.

In the form illustrated in Figs. 1 and 2 the case is provided with a circular shaped 45 wall 9 containing a slot 10, for the reception of a pin 11, attached to a collar 12, which is connected to the upper bracket 6. A circular cup or container 13 is supported in 50 said case 7, which has perforations 14 in the side wall and bottom thereof; a pin 15 is provided in the center of the bottom to hold the citrus fruit in position, and a flange 55 16 on the upper end of said container; said flange extends laterally outward and is supported on the ring 17 on the inner wall 9 of the case.

An opening 17' is provided in the bight

of the bracket 6 in which a pair of co-operating squeezers 18 is inserted and is pivotally retained by means of a pin 19. Each squeezer is provided with an eye or finger 60 hole 20 on the upper or outer end and a closure blade 21 at the lower end within the frame, adapted to operate in the perforated container.

In the modified form disclosed in Figs. 3 65 and 4, the device is illustrated rectangular in shape.

In this modification the outer frame includes an upper bracket 26 and a rectangular shaped case 27, removably attached thereto, which has an opening 28 in the depressed lower portion thereof. Suitable fastening means, as a hook 29 and eye 30, are provided on the collar 31 of the case 27 and the band 32 of the bracket 26, respectively. 70

A rectangular cup or container 33 is supported in said case 27, and has perforations 34 in the sides and bottom thereof. The container 33 is provided with a pin 35 at the center of the bottom to hold the citrus fruit in position, and a laterally extending flange 36 at the upper end, which flange is supported on ribs 37 formed on the inner side walls of the case. An opening 38 is provided in the upper end of the bracket, in which a pair of co-operating squeezers 39 is inserted and pivotally retained by means of a pin 40. The upper ends of the squeezers 39 are supplied with eyes or finger holes 41 and the lower ends with blades 42 containing flanges 43 extending at right angles to the main blade, and arranged offset with respect to the opposing flanges on the co-operating squeezer blade. 80

In operation, a half or portion of lemon 95 or similar citrus fruit is placed on the pin in the container with the cut portion downwards; the upper or bracket part is then fastened onto the lower or case part and the squeezers are operated by engagement of 100 the fingers in the eye portions. In either form of the invention, the device may be rested upon a cup or glass while the juice is being squeezed out, or the device may be held over the edibles and the juice directly 105 squeezed thereon. The blades have been arranged in scissors fashion to force the juice from the fruit portion to be expressed downwardly into the container, avoiding any upward spray of the juice. The con- 110

tainer with the pulp of the citrous fruit may now be taken out of the case, the pulp removed and the device washed.

It is thus evident that I have provided a 5 lemon squeezer adapted for direct individual use at the table and which will obviate the unpleasant occurrences above set forth.

While I have illustrated and described the 10 preferred form of construction for carrying my invention into effect, this is capable of variation and modification without departing from the spirit of the invention. I, therefore, do not wish to be limited to the precise 15 details of construction set forth, but desire to avail myself of such variations and modifications as come within the scope of the appended claims.

Having described my invention, what I 20 claim as new and desire to secure by Letters Patent is:

1. In a device of the class described, a 25 frame member, opposing squeezers pivotally mounted in said frame member, and a fruit container detachably supported in said frame.

2. In a device of the class described, a 30 frame member comprising a bracket and a supporting member, a pair of squeezers pivoted in said bracket, and a container detachably supported in said supporting member.

3. In a device of the class described, an 35 outer frame, a perforated container supported therein, an outlet on said frame exterior of said container, and a pair of pivoted squeezers operably mounted in said frame.

4. In a device of the class described, an 40 outer frame having an outlet near the lower end, a perforated container supported in said frame above said outlet, and a pair of squeezers pivotally mounted in said frame to operate in said container.

5. In a device of the class described, a 45 frame member having an outlet at the lower end, a perforated container supported in said frame member above said outlet, a bracket at the upper part of said frame member, and a pair of squeezers pivotally mounted in said bracket and operable in said container.

50 6. A fruit squeezer comprising an outer frame, a container supported in said frame, means mounted in said container for hold-

ing fruit at the center thereof, and means mounted in said frame for extracting juice from fruit within said container.

7. A fruit squeezer comprising an outer frame, a perforated container supported in said frame, a fruit holding pin mounted on the inner part of said container, and a pair of squeezers pivotally mounted on said frame to operate within said container.

8. In a device of the class described, a 60 frame comprising a bracket and a case detachably connected together, a pair of squeezers mounted in said bracket, a fruit container supported in said case, and means for operating said squeezers in said container.

9. In a device of the class described, a 65 frame comprising a bracket and a supporting case detachably connected together, a pair of squeezers pivotally mounted in said bracket, a perforated container removably supported in said case, and means for operating said squeezers in said container.

10. A device of the class described, comprising a curved upper bracket and a circular case detachably connected thereto, a circular container removably supported in said case, and a pair of curved squeezers mounted 75 in the bight of said bracket and adapted to operate in said case.

11. In a device of the class described, a 80 frame comprising a bracket and a case detachably connected together, a pair of squeezers inounted in said bracket, a fruit container supported in said case, and an outlet at the lower portion of said case.

12. In a device of the class described, a 85 frame comprising a bracket and a supporting case detachably connected together, a pair of squeezers pivotally mounted in said bracket, a perforated container movably supported in said case, means mounted in said container for holding fruit at the center 90 thereof, and means for operating said squeezers in said container.

In testimony whereof I have signed my 95 name to this specification in the presence of two subscribing witnesses.

WILLIAM E. GRAY.
